(57) **CLAIM**

The ornamental design for a cosmetic skin care device, as shown and described.

DESCRIPTION

2. Cosmetic skin care device

2.1 : Perspective

2.2: Front

2.3 : Back

2.4 : Left

2.5: Right

2.6: Top

2.7: Bottom

The overall shape of the design is vertical, with a slightly thicker top and bottom, and the center is the narrowest; at the upper end of the front side, a square plate-shaped electrode section in which a plurality of electrodes are arranged is attached obliquely to the main body; the main body has an edged shape overall.
